MOLD AND METHOD FOR FORMING THE
BELL OF A BELL-ENDED PIPEHugh F. Kennison, Verona, N. J., assignor to Lock
Joint Pipe Company, East Orange, N. J., a cor-
poration of New Jersey

Application August 19, 1948, Serial No. 45,078

4 Claims. (Cl. 25—128)

1

This invention relates to a mould and a method for making a pipe of the bell and spigot type. An object of the invention is to provide an apparatus and method for applying and finishing a bell for making a concrete pipe with a bell end and in which a prefabricated concrete collar is secured to a prefabricated concrete conduit in such a manner that the interior of the bell can be provided with a smooth surface of desired dimensions during the process of securing the collar and the conduit together.

Another object of the invention is to provide a mould ring adapted to be disposed at the end of a conduit and in extension thereof, and to be used in conjunction with the conduit and a collar to be secured to the conduit as a mould which may be filled with cementitious material whereby the collar is secured to the conduit and the interior of the bell is finished to the precise dimensions desired. The mould ring is so constructed as to be readily removable from the interior of the bell when the filling material has hardened.

It is desirable that the interior surface of the bell of a concrete pipe be smooth, particularly when it forms part of the joint which is sealed when a spigot on which a gasket is mounted is engaged with the bell. This is because a rough surface on the bell will abrade the gasket and in some cases may prevent the closing of the joint. Moulding processes commonly employed cannot be depended upon to provide concrete surfaces for the interior of a bell which are sufficiently smooth and accurate to effect an efficient seal and to assure uniform sealing conditions for all of the joints in a pipe line, and it is therefore an object to improve bell and spigot joints for concrete pipes.

Other objects and advantages of the present invention will be hereinafter set forth in the accompanying specification and claims and demonstrated by the drawings which show by way of illustration a preferred embodiment of the principle of the invention and the best mode which has been contemplated for applying that principle.

Referring to the drawings,

Fig. 1 illustrates a prefabricated concrete conduit;

Fig. 2 is an exterior view of a pipe of the present invention;

Fig. 3 is a section of part of a mould including an end of the conduit, and showing the filling material tamped into place between the interior surface of the concrete collar and the exterior

2

surfaces of the concrete conduit and mould ring; Fig. 4 is a section on line 4—4 of Fig. 3;

Fig. 5 illustrates the manner in which the pipe and the mould ring are removed from the base portion of the mould;

Fig. 6 is a section through an interior of a portion of the mould ring and pipe;

Fig. 7 illustrates the manner in which the mould ring is contracted to remove it from engaging relationship with the interior of the bell; and

Fig. 8 is a detail of the mould ring showing a removable segment and adjacent ends of the mould ring.

The conduit portion of the pipe and the collar which is to constitute the main portion of the bell end of a pipe are separately fabricated and they may each be moulded or cast in any well-known manner, such as by the use of stationary or centrifuging moulds. These members may be made of concrete or of other mouldable material which is serviceable for use as conduits upon hardening, and they may be provided with or without steel reinforcing. An advantage of making concrete pipes in accordance with the present invention lies in the fact that economical moulding methods may be used to form the conduit and the collar. A plain conduit having parallel surfaces traced by the four sides of a rectangle rotated around a directrix parallel to one of its sides is appropriate, but in Fig. 1, a conduit 1 is illustrated which is provided with an annular recess 2 having a sloping surface 3 by which the conduit is adapted for association with the support which is described hereinbelow. The other end of the conduit may be finished in like manner, if desired, or may be left plain, as illustrated in Fig. 1, or may have a gasket-receiving groove 4 formed therein, as illustrated in Fig. 2.

A form of pipe which may be made in accordance with the principles of the present invention is illustrated in Fig. 2. This pipe includes a prefabricated conduit 1, a prefabricated collar 5 and filling material 6, which, together with the collar 5, forms the bell of the pipe and secures the collar 5 to the conduit 1.

As illustrated in Figs. 3, 4 and 5, a mould by which the bell may be formed, includes a base 7 in the form of a plate and to which is attached a pipe-supporting ring 8 or other supporting elements which may constitute a number of posts circumferentially spaced below the conduit. The ring 8 or other supports may be secured to the plate 7 in any manner desired. A

series of bolts 9 may be spaced in a flange at the interior of the supporting ring.

The support or ring 8 is provided with a radial surface 10 and a conical surface 11 by which the end of the conduit 1 is supported and centralized with respect to the axis of the ring. The conical surface 11 has a slope corresponding with the slope of the surface 3 at the end of the conduit. If the end of a conduit is plain, that is, has its entire end surface in a plane normal to the axis of the conduit, as illustrated at the right-hand end of Fig. 1, the conduit supporting surface 10 would be horizontal throughout, and guiding means fastened to the interior of the support 8 and extending into contact with the inner surface of the conduit would serve for centralizing the conduit with respect to the support. The height of the extreme end of the conduit from the base 7 is determined by the length of the bell desired. The support 8 is provided with a cylindrical surface 12 which contacts with and holds the mould ring 13 in concentric relationship with the wall of the conduit. The plate 7, support 8 and mould ring 13 are preferably made of steel.

The outside surface 14 of the mould ring 13 is highly polished and is finished to a true cylindrical surface to form the interior bearing surface 15 of the bell and may be provided with an outwardly sloping surface 16 if a flare is desired at the mouth 17 of the bell. As illustrated in Fig. 3, the diameter of the outer cylindrical surface 14 of the mould ring 13 is substantially the same as the outer diameter of the conduit 1, but it will be understood that it is important that the diameter of the surface 14 be such as to form a bearing surface 15 at the interior of the bell which will complement and telescopically engage with the bearing surface of the spigot with which it is to be joined, whatever its diameter may be. In the present case the spigot has an exterior bearing surface 18 of substantially the same diameter as the exterior of the conduit.

The prefabricated concrete collar 5 constitutes a part of the mould and it is placed exteriorly of the mould ring 13 and in concentric relation thereto, as illustrated in Fig. 3. The concentricity of the collar 5 with the remaining portions of the mould and the conduit may be assured by the engagement of a collar-encircling sleeve 19 with a shoulder or flange 20 which is circular with respect to the axis of the mould. When the mould ring 13 and the concrete collar have been positioned upon the base 7, the conduit is mounted upon the support and is properly centralized.

The interior of the bell is formed by filling material 6 which is tamped into place between the ring 13 and the collar 5, and the collar is attached to the conduit by continuing the placing and tamping of the material until the space between the collar and the conduit is filled. The filling material may constitute any of the commercially used jointing materials which are suitable for producing a smooth surface when placed against a polished form and which becomes strong enough for caulking upon hardening. Mortar comprising dry cement and sand slightly moistened with water and tamped into place has been found to be suitable.

The exterior surfaces 14 and 16 of the mould ring 13 are ground smooth to true cylindrical and sloping surfaces, respectively. A removable segment 22, as best seen in Figs. 4, 6 and 8, is

provided to facilitate the removal of the mould ring 13 from the bell after the filling material has set. The ring has been finished to its correct dimensions. A removable segment 22 is cut from the ring preferably after bar 23 carrying bosses 28 and 31 is attached to the segment by such means as screws 24, 25, etc. The bores of the bosses 26, 27 of the ring and the bore of boss 28 are drilled in alignment, and the bores of the bosses 29, 30 are drilled in alignment with the bore of the boss 31 at the other end of the bar 23. By following this procedure and severing the removable segment 22 from the mould ring after the mould ring has been finished, the shape of the mould ring when the segment is in place will be assured. The segment 22 is maintained in place as a part of the mould ring by the pins 32 and 33, Fig. 6. When the mould ring is assembled with the removable segment 22 in position, the exterior surfaces of the mould ring define true surfaces of revolution.

After the filling material 6 has hardened, the pipe is removed from the base of the mould either by lifting the pipe from the base, as illustrated in Fig. 5, or by knocking the base away from the pipe. In view of the compactness of the filling material produced by tamping, the removable mould ring will adhere to the filling material and become detached from the base when the pipe is separated from the base. This relationship of the mould ring and the pipe is illustrated in Figs. 5, 6 and 7.

The mould ring may easily be detached from the interior of the bell after pins 32 and 33 have been withdrawn and the segment 22 is released from the remaining portion of the ring. The pins 32 and 33 are then used to engage the links 35 and 36 of a tool 37, Fig. 7, by which the remaining portion of the ring is relieved from the bell.

The tool 37 is pivotally connected with the adjacent ends of links 35 and 36 and upon rotation of the tool clockwise, as shown in Fig. 7, a toggle effect is exerted upon the ends of the mould ring and the ring is contracted and drawn away from adhering relationship with the filling material 6. The surface of the filling material interiorly of the bell, which formerly was in contact with the exterior surface of the mould ring, is left smooth and true as moulded by the mould ring, and no further finishing is necessary to complete the pipe. When the filling material has completely cured, the pipe is serviceable and ready for use.

A concrete pipe manufactured in the manner described has the advantage of having a strong bell owing to the integrality of the collar 10 and the monolithic layer of dense filling material of substantial thickness which is bonded to the collar and the conduit and provides an ideal interior bearing surface for the bell. The interior bearing surface 15 is smooth and has precisely the dimensions desired. Especially when the sealing gasket is composed of a relatively non-compressible material, such as rubber, the space for enclosing the gasket within a closed joint must be accurately determined within close tolerances. If the space confining a gasket of a given volume is too large, an adequate pressure-proof seal cannot be attained, and if the space is too small, either the joint cannot be closed, or a great deal of force must be exerted on the pipes in order to couple them together. The polished exterior surface of the mould ring 14 assures accuracy and produces a smooth interior

for the bell which minimizes the possibility of abrading or otherwise injuring the gasket when pipes are coupled.

What is claimed is:

1. A mold for attaching a collar to a conduit and for forming the interior of a bell at the end of the conduit, comprising a base, a mold ring for forming the interior of a bell, means carried by said base for supporting a conduit from one end and for holding said mold ring in concentric relationship with respect to said conduit and with the mold ring disposed adjacent the end of the conduit, means for locating a collar concentrically to said conduit and to said mold ring, said collar having an interior surface spaced from the exterior surfaces of said conduit and mold ring for providing an annular recess for receiving filling material.

2. The combination set forth in claim 1 in which the mold ring has at least one section which can be removed from the mold ring in order to detach the mold ring from the filling material after the filling material has hardened.

3. A mold for attaching a collar to a conduit and for forming the interior of a bell at the end of the conduit comprising a base, a mold ring for forming the interior of a bell, said mold ring having a removable segment, means for supporting a conduit from one end in spaced relation to said base, said means being constructed and arranged to maintain said mold ring in concentric relation to said conduit, and means for mounting a collar in spaced relation to said conduit and mold ring for providing an annular space outside of said conduit and mold ring for receiving filling material, whereby said collar is attached to the conduit and the interior of the bell is formed exteriorly of the mold ring.

4. A method for making a pipe of the bell and spigot type having a concrete conduit portion and a bell, comprising the steps of arranging

said conduit portion and a concrete collar having an inner diameter greater than the outer diameter of said conduit portion in alignment on a common vertical axis with the collar overlapping and extending beyond the lower end of said conduit portion and retaining such arrangement of the conduit portion and collar by a mould having a smooth cylindrical surface disposed below the lower end of said conduit portion opposite to and spaced from said collar and adapted to form an inner face of desired dimensions for said bell, filling the annular space within said collar with a relatively dry mortar mix, completing the bell by tamping said mix to form a monolithic layer of dense mortar in bonded relation to said collar and conduit portion and to impart to the portion of said layer surrounding the mould the smooth surface of said mould, and removing said mould from said pipe after the mortar mix has hardened.
